STRAP FOR MUSICAL INSTRUMENT

Bennie Steinborn, 1619 N. Hoyne Ave.,
Chicago, Ill. 60647

Filed Oct. 31, 1966, Ser. No. 4,485

Term of patent 3½ years

(Cl. D2—393)

FIG. 1 is a top plan view of a strap for a musical instrument showing my new design, the ornamental decoration being continuous as indicated by dot dash lines, the broken away sections being for convenience of illustration, and the broken away ends indicating indeterminate length;

FIG. 2 is a bottom plan view thereof;

FIG. 3 is an enlarged fragmentary side elevational view as seen in the direction of the arrows 3—3 of FIG. 1;

FIG. 4 is a cross sectional view of FIG. 3 taken on the line 4—4; and

FIG. 5 is a top plan view of another embodiment of the design of FIG. 1.

The essential features of my design reside in the full line disclosure.

I claim:

The ornamental design for a strap for musical instrument, as shown and described.
